UNITED STATES PATENT OFFICE.

WILLIAM E. STAFFORD, OF OSWEGO, NEW YORK, ASSIGNOR TO THE DIAMOND MATCH COMPANY, OF CHICAGO, ILLINOIS, A CORPORATION OF ILLINOIS.

VENEER-LATHE.

1,293,230.

Specification of Letters Patent.

Patented Feb. 4, 1919.

Application filed April 19, 1917. Serial No. 163,159.

To all whom it may concern:

Be it known that I, WILLIAM E. STAFFORD, a citizen of the United States, and resident of the city and county of Oswego and State 5 of New York, have invented certain new and useful Improvements in Veneer-Lathes, of which the following is a specification.

This invention relates to that class of veneer lathes wherein scoring tools are arranged in co-operative relation to a peeling knife so as to form score lines in and longitudinally of the surface of the veneer as rapidly as the veneer is peeled from the log; the sheet material thus produced being especially though not exclusively designed 15 for use in the manufacture of match-box shucks or covers.

The object of my invention is to provide a lathe whereby veneer of uniform thickness having therein score lines of uniform character are produced.

To this end the invention, generally stated, comprises means whereby the scoring tools are mounted and arranged to act upon 25 the surface of a rotating log concurrently with the peeling knife and at a constant angular relation to the varying peripheral curvature of the log; such means, in the preferred form of embodiment of my invention 30 herein illustrated, comprising a structure mounted on the traveling peeling head or carriage in such a manner as to have capacity for independent oscillatory movement thereon; scoring tools positioned on 35 said structure to act upon the surface of the log directly in advance of the peeling knife, and correlated cam devices whereby the said structure is gradually tilted progressively with the veneer cutting operation so as to 40 maintain the defined relation between the scoring tools and the adjacent surface of the rotating log.

The invention also comprises features of construction and combinations of parts 45 which will be hereinafter described and claimed.

In the drawings—

Figure 1 is a plan of a veneer lathe embodying the principle of my invention. 50 Fig. 2 is a side elevation of the improved lathe.

Fig. 3 is a sectional detail of the tool holder and adjuncts, as on the line 3—3 of Fig. 1.

Fig. 4 is a perspective view of one of the

scoring tools, showing its relation to the surface of the log.

Referring to the drawings, 10 designates the supporting frame of a typical veneer lathe, and 11 the main shaft journaled in 60 suitably-disposed boxes on the frame. 12 designates mandrels having their bearings in boxes on lateral uprights on the frame, and 13 center plates borne by the mandrels. The mandrels have spur wheels 14 in mesh 65 with pinions 15 on the main shaft, whereby the center plates are concurrently rotated at a relatively low speed. One of the mandrels is adjustable toward and from the other in order to facilitate the application of a cylindrical log to or its removal from the centers 70 as desired.

16 designates a carriage which is mounted on horizontal guides on the sides of the bed, and 17 a peeling knife which is carried by 75 the carriage and is advanced thereby against the rotating log at a uniform speed relatively to that of the log so as to cut progressively from the latter a spiral sheet of veneer of uniform thickness throughout its 80 length and breadth.

The timely advancement of the carriage and peeling knife in relation to the rotary travel of the surface of the log is effected through suitable connections with the main 85 shaft. Accordingly the shaft 11 bears a worm 18 which meshes with a worm wheel 19 on a shaft 20 extending longitudinally of the supporting frame. The rearward end of the shaft 20 is provided with a gear 90 wheel 21 which is connected through transmission gears 22 with a gear wheel 23 on the outer or rearward end of one of a pair of spaced lead-screws 24 which extend beneath the slide-rest and engage internally-threaded 95 projections 25 on the latter. The two lead screws are geared together for concerted rotation by bevel wheels 26 thereon co-acting with similar wheels 27 on a transverse shaft 28 at the rear of the bed. 100

29 designates a platform overlying the carriage and extending rearwardly from a point adjacent the peeling knife, so as to receive the veneer as rapidly as it is cut and deflect it toward the rear of the machine. 105

The mechanisms above referred to being of known construction and operation need no particular description herein; it being noted that the typical lathe shown has been selected for illustrative purposes only. 110

30 designates a row of spaced scoring tools each of which comprises a shank having a V-shaped chisel or cutting point 31. These tools are mounted and arranged to act upon 5 the surface of the log directly in advance of and concurrently with the peeling knife. In pursuance of my invention such tools are maintained at a constant angle in relation to the varying circumference of the log 10 so as to produce in the surface of the latter parallel scores of uniform character extending longitudinally of the veneer. The scoring tools are borne by an oscillatory structure which is supported on the carriage, said 15 structure, in its preferred form, comprising a cross-bar 32 provided at its ends with rearwardly-extending arms 33 in which are supported the ends of a transverse shaft 34 at a suitable distance in rear of the bar. This 20 bar is mounted on the carriage in such a manner as to have thereon a horizontal axis of oscillation; that is to say, the bar is provided near its respective ends with two vertically-adjustable screws 35 the lower ends 25 of which project below the bar and rest in socket bearings 36 affixed to the carriage. The sockets 37 in these bearings are elongated so as to permit of slight forward and rearward movement therein of the pivot 30 screws during variable angular movements of the oscillatory structure. By manipulating the screws 35 the bar may be nicely adjusted vertically in order to insure corresponding adjustment of the scoring knives 35 relatively to the acting edge of the peeling 35 knife.

The respective ends of the shaft 34 are journaled in segmental bearing blocks 38 which are slidingly mounted in upright cam 40 guides 39 formed in brackets 40 affixed to the carriage. The shaft 34 is also provided adjacent the respective cam guides with anti-friction rollers 41 which ride upon parallel cam rails 42 of appropriate formation that extend longitudinally of and are 45 conveniently supported upon the lathe bed. As clearly shown, the track constituted by the cam rails gradually inclines upwardly and forwardly from a point a suitable distance in rear of the cylindrical log when 50 the peeling knife and scoring tools are first engaged with the log; the coöperative relation of such cam rails, the cam guides and the pivot support for the bar 32 being such 55 that the longitudinal axis of the shaft 34 is in horizontal alignment with the axis of rotation of the log, or substantially so. Thus the oscillatory structure and the scoring tools are in substantially horizontal position 60 with the acting ends of such tools bearing a definite angular relation to the adjacent peripheral surface of the log in order to produce therein a series of grooves of predetermined form and depth. The degree of 65 upward inclination of the cam track and

the relative curvature of the cam guides are such that as the diameter of the log is progressively and uniformly reduced by the advancing peeling knife, the oscillatory structure and its scoring tools are gradually 70 tilted about the pivot support so as to maintain constant the angular relation of said tools and the surface of the rotating log, thus insuring score lines of uniform character in and throughout the length of the 75 veneer without the otherwise necessity of varying the depth of cut of the peeling knife.

It is to be noted that the contour of the cam guides 39 and their disposition in respect to the scoring tools and to the axis 80 of oscillation of the tool bar, are such that the forward tipping movement of the cutting points of the said tools is prevented, except when the angular adjustment of the 85 tools is dictated by the stationary cam track 42 in order to compensate for the increasing curvature of the log as its diameter is reduced by the advancing peeling knife.

In Fig. 2 the full lines show the initial 90 relative positions of the veneer peeling knife and the scoring tools and their respective supporting parts upon the commencement of the peeling operation at the outside of the cylindrical log, and the dotted lines indicate their relative position when the log has 95 been reduced to the central core.

The novel organization above described is not only simple and durable in construction, but in operation it effects and maintains accuracy and uniformity of contact 100 between the functional ends of the scoring tools and the varying circumference of the log as previously mentioned.

My invention is not limited to the details 105 of construction herein disclosed as the same may be variously modified within the principle of my invention and the scope of the appended claims.

I claim—

1. In a veneer lathe, the combination with 110 means for rotating a cylindrical log, a peeling knife, its carriage, and means for actuating said carriage, of a surface scoring tool having a V-shaped cutting portion, a support therefor on said carriage having capacity for movement independently of the carriage, and automatic mechanism for gradually varying the angularity of said support in respect to its path of travel toward 115 the log.

2. In a veneer lathe, the combination with 120 means for rotating a cylindrical log, a peeling knife, its carriage, and means for actuating said carriage, of a surface scoring tool 125 having a V-shaped cutting portion, a support therefor on said carriage having capacity for movement independently of the carriage, automatic mechanism for gradually varying the angularity of said support in 130

respect to its path of travel toward the log, and controlling means co-acting with the traveling support to prevent displacement of the scoring tool from its prescribed angular cutting positions.

3. In a veneer lathe, the combination with means for rotating a cylindrical log, a peeling knife, its carriage and means for actuating said carriage, of a surface scoring tool

10 having a V-shaped cutting portion, an oscillatory support therefor on said carriage, and mechanism for gradually tilting said support progressively with the advancement of the carriage toward the axis of rotation of the log, whereby a constant angular relation is maintained between the scoring tool and the adjacent surface of the rotating log.

4. In a veneer lathe, the combination with means for rotating a cylindrical log, a peeling knife, its carriage, and means for actuating said carriage, of a surface scoring tool having a V-shaped cutting portion, an oscillatory support therefor on said carriage, a stationary cam track extending longitudinally of the path of the carriage, and operative connection between the support and the cam track, whereby said support and its scoring tool are gradually tilted progressively with the advancement of the carriage

30 toward the axis of rotation of the log.

5. In a veneer lathe, the combination with means for rotating a cylindrical log, a peeling knife, its carriage, and means for actuating said carriage, of a surface scoring tool having a V-shaped cutting portion, an oscillatory support therefor on said carriage, a stationary cam track extending longitudinally of the path of the carriage, operative connection between the support and the

40 track, a cam guide on the carriage, and operative connection between the support and said cam guide.

6. In a veneer lathe, the combination with means for rotating a cylindrical log, a peeling knife, its carriage, and means for actuating said carriage, of a surface scoring tool, an oscillatory support therefor comprising a tool-bearing member and means for ver-

tically-adjusting said member in respect to its axis of oscillation, and mechanism for gradually tilting said support progressively with the advancement of the carriage toward the axis of rotation of the log.

7. In a veneer lathe, the combination with means for rotating a cylindrical log, a peeling knife, its carriage, and means for actuating said carriage, of a surface scoring tool, an oscillatory support therefor on said carriage, having a rearwardly extended portion and lateral track rollers on said portion, a stationary cam track for said rollers comprising corresponding rails spaced apart having upwardly and forwardly inclined portions, whereby the said support is gradually tilted during the advancement of the carriage toward the axis of the log, and means on the carriage co-acting with the said support and the cam track to prevent independent forward tilting of the advancing tool support.

8. In a veneer lathe, the combination with means for rotating a cylindrical log, a peeling knife, its carriage, and means for actuating said carriage, of a surface scoring tool, an oscillatory support therefor on said carriage, having a rearwardly extending portion and lateral slide members and lateral track rollers on said portion, a stationary cam track for said rollers comprising corresponding rails spaced apart having upwardly and forwardly inclined portions, whereby the said support is gradually tilted during the advancement of the carriage toward the axis of the log, and up-standing spaced cam guides for the slide members, said guides being mounted on the carriage and being arranged to co-act with the said support and the cam track to prevent forward tilting of the advancing tool support independently of the motion determined by the cam track.

Signed at the city and county of Oswego, and State of New York, this 16th day of April, A. D. 1917.
